D. EVANGELISTA,
APPARATUS FOR STOPPING TRAINS,
APPLICATION FILED DEC. 22, 1916.

Patented Feb. 25, 1919.

UNITED STATES PATENT OFFICE.

DOMENICO EVANGELISTA, OF NEW YORK, N. Y., ASSIGNOR OF ONE-FIFTH TO EMILIO PETRILLO, ONE-FIFTH TO ERMINIO CARIDEO, AND ONE-FIFTH TO ANTONIO MARANO, ALL OF MOUNT VERNON, NEW YORK, AND ONE-FIFTH TO FRANK A. BELLUCCI, OF CORONA, NEW YORK.

APPARATUS FOR STOPPING TRAINS.

1,295,462.

Specification of Letters Patent. Patented Feb. 25, 1919.

Application filed December 22, 1916. Serial No. 138,372.

To all whom it may concern:

Be it known that I, DOMENICO EVANGELISTA, a subject of the King of Italy, residing in the borough of Manhattan, city 5 of New York, and State of New York, have invented certain new and useful Improvements in Apparatus for Stopping Trains, of which the following is a specification.

My invention relates to systems for stopping trains, both electric and steam, and has for its main object to provide improved means whereby trains at crossings and on the same track will be prevented automatically from collision.

My invention also embodies certain minor details of construction in the apparatus for accomplishing the main object of the invention, as will be hereinafter more definitely pointed out and claimed, reference 20 being had to the accompanying drawing, in which:—

Figure 1 is a diagrammatic plan view of a railway track crossing, showing my improved train stopping apparatus in operative position in respect thereto.

Fig. 2 is an enlarged detail plan view of the circuit breaking apparatus and its operating parts.

Fig. 3 is an enlarged detail plan view 30 of the air-brake setting mechanism and its operating parts.

Similar numerals of reference denote corresponding parts in the several views.

In the said drawing, and referring more particularly to Fig. 1, the reference numerals 1 indicate the rails of a railway track, and 2 the rails of a similar track crossing the tracks 1 at an angle thereto. The lines formed by the tracks 1 and 2 will be equipped similarly with my improved train stopping apparatus, and a description of one of the same will be understood to apply equally to the other. Thus, between tracks 1 to the left is a base plate 3, upon which is pivoted at 4 a cross tripping lever 5, having a projection 6 thereon, adapted to be contacted with by a suitable tripper on the engine of a train moving from left to right, said lever 5 being normally retracted to the position shown in Fig. 1 by a suitable coiled spring 7, and being adapted to be moved at its free end toward the right by the action of the trip-

per. Pivoted to said lever 5 is a connecting piece 8, to which a rod 9 is fixed, the latter being controlled in its longitudinal movement by a guide 10 on the base plate 3. Lying normally within the path of longitudinal movement of the extension of the rod 9 is a similar longitudinally movable rod 11, having a pivot at 12 and extending over the crossing of the tracks, said rod 11 being connected at the crossing to a bell-crank 13, the other arm of which is pivoted to a rod 14 running between the tracks 2. The outer end of said rod 14 is in the path of the end 15 of a V-shaped plate 16, slotted at 17 to engage a pin 18 fixed to a base plate 19, and normally retained in the position shown in Fig. 2 by a spring 16^a disposed between abutments on said plate 16 and the base plate 19. Said plate 16 when in the position shown in Figs. 1 and 2, contacts with two terminal plates 20, which are in the circuit supplying the current to the tracks 2, a portion of the circuit being shown in dotted lines.

Just in front of the base plate 19, pivoted at 21, is a bell-crank 22, slotted at 23 to engage a pin 24 on the rod 14, the other end of said bell-crank having pivoted thereto a lever 25, slotted at 26 to engage a pin 27 on the rod 11, said pin 27 and lever 25 being connected by a retracting spring 28.

The rod 11 extends across the crossing beyond the bell-crank 13 and is in alignment with a head 29 fixed to a lever 30 pivoted at 31, and at its opposite end connected by a rod 32 with a bar 33, that in turn is connected to a lever 34, pivoted at 35 to a base plate 36, and provided with a projection 37 at its free end, said lever being normally retained in the position shown in Fig. 1 by a spring 38.

The operation of these portions of the apparatus is as follows:—A train moving from left to right on the track 1, will, in passing over the lever 5, and by contact of its tripper with the projection 6 thereon, swing said lever 5 on its pivot 4 to the right, which in turn moves rod 9, and said rod by contact with the end of the rod 11 will move the latter, which will in turn operate bell-crank 13, forcing rod 14 outward against the head 15 of plate 16, and causing the latter to move from contact

with the terminal plates 20, thereby breaking the electric circuit to tracks 2, and causing the stoppage of any train approaching on said tracks while a train is passing on tracks 1 over the crossing. After the train has passed on tracks 1 over the crossing, the tripper thereon will contact with the projection 37 on lever 35, moving the free end of the latter to the right against the tension of the spring 38, thereby rocking the lever 30 and its pivot 31, and, through the head 29, forcing the rod 11 and its connected parts back to their initial position, which will cause the plate 16 again to contact with the terminal plates 20 and close the circuit on tracks 2, so that a train thereon may proceed.

It will be understood that a similar break in the circuit on tracks 1 will occur should a train on tracks 2 reach its lever 5 first, the operation being such that the crossing train first to reach its lever 5 will stop traffic on the other track but itself will be free to proceed over the crossing.

In order that my device also may set the air brakes of a train and thus be effective with steam trains, as well as electric trains, I provide the following apparatus:—Fixed to the rod 14 is a bar 39, bolted to a plate 40 slidable between guides 41 on a suitable base plate (not shown), said plate 40 being slotted at 42, and being provided on one side of said slot with teeth 43, adapted to mesh with a toothed gear 44, mounted upon the base plate supporting the sliding plate 40, said toothed gear having connected to its shaft a bar 45, which is rotated together with said gear when the latter is actuated. Thus, when the rod 14 is forced to the left in such manner as to break the circuit to the tracks 1, its movement in that direction correspondingly will move plate 40 to the left, thereby rotating the toothed wheel 44, and through it the bar 45 to the dotted line position shown in Fig. 3. This will cause said bar 45 to lie in position to be contacted with by a tripper on an approaching engine, said tripper being connected with the air-brake system of the engine, whereby said air-brake mechanism will be set by said contact, and the train automatically brought to a stop. This air-brake setting mechanism I have shown only between the tracks 1 to the left, but it will be understood that it is to be located between the tracks 2 and between the crossing and the circuit breaking mechanism carried by plate 19. So also I have shown the circuit breaking mechanism between tracks 1 and 2 at one side only, whereas it will be understood that said mechanism will be duplicated upon the other

side, and the resetting mechanism carried by plate 36 will also be duplicated upon the opposite side, so that the system will operate for trains running in both directions and on both tracks.

It will be observed that when the rod 9 actuates the rod 11 longitudinally, the pin connection 27 between said rod 11 and the lever 25 will cause the latter to rock on its pivotal connection with the bell-crank 22 to the dotted line position shown in Fig. 2, but without in any way affecting said bell-crank, and when said rod 11 is returned to its initial position, through the operation of the lever 27, the lever 25 will also return to its initial position due to the tension of the spring 28. But when the rod 14 is actuated to break the circuit at 20, the pin 24 thereon will, through its engagement with the bell-crank 22, rock the latter on its pivot 21, and thereby force the lever 25 to the dotted line position shown in Fig. 2, which in turn will carry with it that portion of the rod 11 to the left of the pivot 12, said rod 85 then assuming the dotted line position shown in Fig. 2 and being out of alinement with the rod 9. The result of this is that should said rod 9 be actuated longitudinally through the movement of a train passing over lever 5, it would have no effect upon the rod 11 in breaking the circuit upon the opposite track, as the parts 9 and 11 will be out of alinement. For this reason, when the circuit is broken in the mechanism between the tracks 2, by the movement of a train on tracks 1, the passage of a train on tracks 2 past the lever 5 before it comes to a stop, due to the breaking of its circuit, will not similarly operate the circuit breaker 100 between tracks 1, and, therefore, will not affect the movement of the train on said tracks 1.

Having thus described my invention what I claim as new and desire to secure by Letters Patent, is:—

A train stopping system, comprising rod connections adapted to be operated by trains to break an electric circuit controlling another train, bell-cranks operated by said rod connections and controlling portions of the opposite rod connections adapted to move them out of operative alinement whereby the setting of one set of rod connections to break the electric circuit controlled thereby automatically will shift a portion of the other rod connection to prevent its operation.

In testimony whereof, I hereunto set my hand this 16th day of December, 1916.

DOMENICO EVANGELISTA.
